UNITED STATES PATENT OFFICE.

MORRIS FINK AND MAE J. DUNN, OF CHICAGO, ILLINOIS, ASSIGNEES TO THE WARREN FEATHERBONE COMPANY, OF THREE OAKS, MICHIGAN, A CORPORATION OF MICHIGAN.

COLLAR.

1,193,885.

Specification of Letters Patent.

Patented Aug. 8, 1916.

Application filed January 6, 1915. Serial No. 721.

To all whom it may concern:

Be it known that we, MORRIS FINK and MAE J. DUNN, citizens of the United States, and residents of the city of Chicago, in the county of Cook and State of Illinois, have invented certain new and useful Improvements in Collars, of which the following is a specification.

Our invention relates to collars for women and more particularly to a combined collar and guimpe.

The principal object of the invention is to devise a structure that will be attractive in appearance, easily attached and detached, and when applied will fit the neck of the wearer closely and will not become displaced.

In the accompanying drawing: Figure 1 is a perspective view of my improved collar showing its application to the wearer. Fig. 2 is a plan view of my improved collar.

Referring now more particularly to the drawing, our structure comprises, preferably, five stays or collar supports comprising a central stay 3, end stays 4 and 5 and two intermediate stays 6 and 7. These stays are secured to one or more sections of material, preferably lace and constituting the collar. The fabric comprising the collar is so cut that its upper edge is shorter than its lower edge and with the stays arranged thereon so as to converge toward the upper edge of the collar, with the exception of the center stay which is arranged preferably at right angles to the upper edge of the collar.

Extending from the stays 4 and 5 are two sections of fabric 8 and 9, preferably lace, which may be of any desired form but the upper edges of which are attached to the stays 4 and 5 at a point below the upper edge of the collar.

A binding strip 10 is secured to the lower edge of the collar as well as the lower edges of the guimpe sections 8 and 9, while the upper edge of the collar, as well as the upper edges of sections 8 and 9, may be trimmed with a lace edging 11.

A strap 12, which may be a velvet ribbon or any other desired material, is secured at one end to the upper end of one of the stays 4 or 5, herein shown as secured to the upper

end of the stay 4. The outer end of the strap 12 is provided with two parts 13 of snap fasteners, and secured to the stay 5 are the complementary parts 14 of the snap fasteners 13.

The structure is applied to the neck of the wearer so that the strap 12 crosses the throat of the wearer whereby the upper end of the collar is secured in place. It is to be noted that the stays 4 and 5 are longer than the stays 6 and 7 so that when the collar is applied these long stays will be flexed to conform to the contour of the neck and body of the wearer whereby the upper end of the stays 4 and 5 are at all times bearing against the wearer's neck and this is also true of the stays 6 and 7 which are longer than the central stay 3.

The guimpe sections 8 and 9 are adapted to be crossed and are so cut as to leave a margin beneath the strap 12 so as to expose the throat of the wearer. The outer garment 15 of the wearer surrounds the lower part of the collar as well as the lower portions of the guimpe thereby holding the collar and guimpe firmly in place and the free ends of the guimpe may be pinned if desired. It is, of course, understood that the stays are constructed of flexible, resilient material so that they will, at all times, conform to the contour of the body or neck of the wearer in bending movements and will thus cause the upper edge of the collar to be held in place.

Having now described the invention; we claim:

1. A collar comprising two relatively long and resilient end stays, intermediate stays less in length than said end stays, a fabric to which said stays are secured, said end stays converging toward the upper edge of said fabric, guimpes secured to said end stays and having their upper edges arranged below the upper ends of said end stays and a strap secured to the upper end of one end stay and detachably connected to the other end stay.

2. A collar comprising a central resilient stay, two long end stays and an intermediate stay interposed between the central and each end stay but less in length than said end stays, a fabric to which said stays are se-

cured, said end and intermediate stays converging toward the top of the fabric, guimpes secured to the end stays and arranged below the upper ends thereof, a binding strip secured to the lower edges of said collar and guimpes, an edging secured to the upper edges of said collar and guimpes and a strap secured to the upper end of one of

said end stays and detachably connected to the other end stay.

MORRIS FINK.
MAE J. DUNN.
